UNITED STATES PATENT OFFICE.

MICHAEL JOHN FITZGERALD, OF LANCASTER, CALIFORNIA.

DESIGN FOR A GAME-BOARD.

45,705.

Specification for Design.

Patented May 5, 1914.

Application filed January 21, 1914. Serial No. 813,591. Term of patent 14 years.

To all whom it may concern:

Be it known that I, MICHAEL JOHN FITZGERALD, a citizen of the United States, residing at Lancaster, in the county of Los Angeles and State of California, have invented a new, original, and ornamental Design for a Game-Board, of which the following is a specification, reference being had to the accompanying drawing, forming part thereof.

The figure is a plan view of a game board, showing my new design.

I claim:

The ornamental design for a game board, as shown.

MICHAEL JOHN FITZGERALD.

Witnesses:

G. A. BROOKS,
F. J. SWAN.
